DESIGN FOR A BUS

George S. Lawson, St. Clair Shores, Mich.

Application October 9, 1946, Serial No. 133,832

Term of patent 7 years

(Cl. D14—3)

To all whom it may concern:

Be it known that I, George S. Lawson, a citizen of the United States, residing at St. Clair Shores, in the county of Macomb and State of Michigan, have invented a new, original, and ornamental Design for a Bus, of which the following is a specification, reference being had to the accompanying drawing, forming a part thereof, and wherein—

Figure 1 is a side elevational view of a bus, illustrating my new design,

Figure 2 is a top plan view of the bus with the left hand front door and step in open position, and Figure 3 is a front elevational view of the same.

Only one side of the bus is illustrated in Figure 1 of the drawing. However, it is to be understood that both sides thereof are similar in design.

I claim:

The ornamental design for a bus, as shown and described.

GEORGE S. LAWSON.
